LUIGI PIGNANELLI, OF TACOMA, WASHINGTON

SHOE

Application filed February 28, 1929. Serial No. 342,869.

This invention relates to an improvement in the construction of shoes, pumps and the like.

Shoes, as heretofore made, have proved unsatisfactory because of furnishing an unsuitable support to the weight of the wearer's body and thus subjecting him to unnatural muscular strains both in standing and when walking. These disadvantages have been 10 partially overcome by inserting within the shoe "arch supporters" and "foot corrective appliances" which afford but temporary relief to the feet when used with low heeled shoes; but are found to be a source of much 15 trouble with other kinds of shoes—especially women's wear—due to the fact that the foot is compressed between the arch supporter and the shoe upper with a consequent cramping of the foot, and the stopping of the blood circulation, resulting in cold feet and other afflictions.

Another objection to the use of an insertable arch supporter is due to its tendency to shift forwardly in a shoe, spreading the foot 25 and the instep and crowding a person's toes.

Moreover, with pumps and other low cut shoes such forward shifting of said devices causes the instep to be elevated to such an extent that the flesh is bulged or protruded 30 above the shoe with a resultant disfigurement of the contour of the foot.

The object of my invention is to obviate the objections above referred to, and others, by the provision of an improved manner or 35 means of making shoes which is adapted to furnish requisite support without distressing the wearer and permitting more freedom in the use of his feet without liability of breaking down the arch of the foot, and properly 40 positioning the foot within the shoe.

Other objects and advantages of the invention will appear in the following description.

The invention consists in the construction of a shoe having a sole provided intermediate 45 its length with a transversely arranged ridge of novel form.

In the accompanying drawings,—

Figure 1 is a side elevation of a portion of a shoe having a sole embodying my improvement; Fig. 2 is a plan view of Fig. 1; Fig. 3

is a view to an enlarged scale, partly in side elevation and partly in longitudinal vertical section of the rear part of a shoe with the upper omitted, and exemplifying by dash lines the contour of a foot and 55 ankle and the bone formation thereof as applied to the shoe; and Fig. 4 is a view in side elevation of a woman's foot wearing a shoe, part of the shoe upper being broken away to disclose a portion of a sole formed in accordance with my invention.

Referring first to Fig. 3, the numeral 5 represents a human foot having a bone structure comprising the astragalus 6 supporting the tibia 7, said astragalus being supported 65 by the heel bone 8, os calcis, and the scaphoid 9.

The heel bone 8 is located at a lower elevation than the scaphoid 9 and is spaced therefrom to provide a recess, into which the fleshy 70 part of the foot extends, as at 10, to progressively greater heights from the outer side of the foot to the inner side thereof.

In carrying out the present invention, I provide, in the top of a shoe sole, a jog 11 75 having at the front thereof a wall part, or shoulder 12, disposed in angular relation of approximately sixty degrees with respect to the plane of the sole portion 13 to the rear of the shoulder.

Said shoulder extends transversely of the shoe and is of gradually diminishing height from the inner side of the shoe to within a short distance of its outer side where it disappears and becomes coextensive as at 14 85 (Fig. 2) with the upper surface of the part 15 of the sole thereof.

Throughout its length—transversely of the shoe—the upper portion of the shoulder 12 is connected with the sole part 15 by a ridge 90 16 which, having a relatively small radius, is comparatively sharp.

The ridge 16 is arranged to extend upwardly to bear against the fleshy foot part 10 between the os calcis and scaphoid bones 8 and 9, the shoulder 12 being disposed in opposed relation with the front of the os calcis or heel bone and bearing against the flesh 17 in front of such bone, serves as a stop to prevent any 95 forward movement of the foot in the shoe. 100

This function of the shoulder is especially important with regard to women's shoes of the character illustrated in Fig. 4 wherein the elevation of the shoe heel or "lift" 18 applied the weight of the wearer's body to cause heretofore, a wedging of the foot downwardly into the forward part of the shoe.

The ridge, furthermore, constitutes a fulcrum, so to speak, which coacts with the ankle bone (astragalus) to afford improved flexibility to the foot and thus enables a person to walk greater distances without tiring than hitherto.

The sole part 15 immediately in front of the ridge 16 slopes transversely to conform with the natural shape of a person's instep and constitutes, in effect, a shelf or platform which serves to most comfortably sustain the arch of the foot.

In the embodiment of the invention illustrated in Figs. 3 and 4, the shoe sole is represented as formed of two layers 20 and 21 coupled together one above the other, and under such a method the upper layer 20 may be formed, as shown, to provide the jog, shoulder and ridge while the under layer 21 is utilized to serve, as at 22, as a tie in producing a triangular construction, whereby the bent portion of the upper layer is prevented from becoming distorted.

What I claim, is,—

1. A shoe having a sole formed to provide in its rear portion a cavity for the heel of the wearer's foot, the front wall of said cavity extending substantially vertically upwardly as a ridge from the top of which the sole extends forwardly as a shelf support for the arch of the foot, the apex of said ridge forming a relatively sharp wedge, said front wall serving as a stop in opposed relation to the heel bone, the upper edge of said ridge and the part of the sole in proximity thereto forward of the ridge being arranged to slope downwardly transversely of the shoe from the inner to the outer side of the foot.

2. In an insole for a shoe, a substantially plane face heel portion, and projecting upwardly substantially vertically at the forward extremity and at the inner arch side thereof, a ridge, said ridge sloping downwardly transversely of said insole and terminating at the outer side in a plane substantially flush with said heel portion, the upper portion of said ridge being adapted to wedge against and support the fleshy part of the foot adjacent the astragalus and between the os calcis and the scaphoid bones of a wearer's foot, projecting forwardly in a gradual declination therefrom to a common plane with the lower portion of said ridge at the fore part of the sole.

3. An insole for a shoe of a conformation adapted to present a ridge projecting upwardly to have the apex thereof in substantial vertical alignment with a center line

taken through the tibia and astragalus bones of a wearer's foot, and wherein the ridge is relatively sharp to wedge against and directly support the fleshy part of the foot intermediate the heel and scaphoid bones.

4. An insole for a shoe of a conformation providing at the inner part of the shoe a ridge projecting upwardly from a plane-faced heel portion thereof, and wherein the apex thereof is relatively sharp and in substantial alignment with a center line taken through the tibia and astragalus bones of a wearer's foot, said apex being of a height sufficient to wedge within the fleshy part of the foot adjacent the astragalus bone to support the latter, said insole projecting forwardly in a gradual declination from said apex to conform to the natural contour of the scaphoid and tarsal bone structure.

Signed at Tacoma, Washington, this 11th day of February, 1929.
